CLAIM

The ornamental design for a cervical traction device as shown and described.

DESCRIPTION

FIG. 1 is a front perspective view of a cervical traction device, showing my new design;

FIG. 2 is a rear perspective view thereof;

FIG. 3 is a top view thereof;

FIG. 4 is a bottom view thereof;

FIG. 5 is a front view thereof;

FIG. 6 is a rear view thereof;

FIG. 7 is a left view thereof; and,

FIG. 8 is a right view thereof.

In the drawings, the broken lines depict portions of the cervical traction device that form no part of the claimed design.
